(57) **CLAIM**

The ornamental design for a hand sign, as shown and described.

DESCRIPTION

FIG. 1 is a left-side elevational view of a first embodiment of a left-hand hand sign according to the invention;

FIG. 2 is a right-side elevational view of the left-hand hand sign of FIG. 1;

FIG. 3 is a reduced scale front elevational view of the left-hand hand sign of FIG. 1;

FIG. 4 is a reduced scale top plan view of the left-hand hand sign of FIG. 1;

FIG. 5 is a reduced scale bottom plan view of the left-hand hand sign of FIG. 1;

FIG. 6 is a reduced scale rear elevational view of the left-hand hand sign of FIG. 1;

FIG. 7 is a perspective view from above the front of the left side of the left-hand hand sign of FIG. 1;

FIG. 8 is a perspective view from below the rear of the left side of the left-hand hand sign of FIG. 1;

FIG. 9 is a right-side elevational view of a second embodiment of a right-hand hand sign according to the invention;

FIG. 10 is a left-side elevational view of the right-hand hand sign of FIG. 9;

FIG. 11 is a reduced scale rear elevational view of the right-hand hand sign of FIG. 9;

FIG. 12 is a reduced scale top plan view of the right-hand hand sign of FIG. 9;

FIG. 13 is a reduced scale bottom plan view of the right-hand hand sign of FIG. 9;

FIG. 14 is a reduced scale front elevational view of the right-hand hand sign of FIG. 9;

FIG. 15 is a perspective view from above the front of the right-side of the right-hand hand sign of FIG. 9; and,

FIG. 16 is a perspective view from below the rear of the right side of the right-hand hand sign of FIG. 9.
